CLAIM

I claim the ornamental designs for a ceiling fan, as shown and described.

DESCRIPTION

FIG. 1 is a bottom perspective view of a ceiling fan showing a first embodiment of my new design.

FIG. 2 is a side elevation view of the ceiling fan of FIG. 1.

FIG. 3 is a bottom plan view the ceiling fan of FIG. 1.

FIG. 4 is a top perspective view of a ceiling fan showing a second embodiment of my new design.

FIG. 5 is a side elevation view of the ceiling fan of FIG. 4.

FIG. 6 is another side elevation view of the ceiling fan of FIG. 4.

FIG. 7 is a top plan view of the ceiling fan of FIG. 4.

FIG. 8 is a bottom plan view of the ceiling fan of FIG. 4.

FIG. 9 is a plan view of a fan blade of the ceiling fan of FIG. 4 shown separately for completeness of illustration; and,

FIG. 10 is a bottom perspective view of the ceiling fan of FIG. 4.

The broken lines on the drawings depict portions of the

ceiling fan that form no part of the claimed design.
